(57) **CLAIM**

The ornamental design for an automobile fuel pump, as shown and described.

DESCRIPTION

FIG. 1 is an isometric view of an automobile fuel pump showing my new design.

FIG. 2 is a top, plan view thereof.

FIG. 3 is a rear elevation thereof.

FIG. 4 is a right side elevation thereof, the left side being a mirror image of the right side; and,

FIG. 5 is a front elevation thereof.

The broken line showing of environmental association matter in FIGS. 1-5 is for illustrative purposes only and forms no part of the claimed design.
